(74) Attorney, Agent, or Firm — Michael N. Cohen;
Cohen IP Law Group PC(57) CLAIM

I claim the ornamental design for the taco shaper, as shown and described.

DESCRIPTION

FIG. 1 is a front perspective view of the taco shaper;

FIG. 2 is a front view thereof;

FIG. 3 is a back view thereof;

FIG. 4 is a right side view thereof;

FIG. 5 is a left side view thereof;

FIG. 6 is a top view thereof; and,

FIG. 7 is a bottom view thereof.

The broken lines shown in the drawings are included for the purpose of illustrating environmental structure and form no part of the claimed design.
